JOHN LYLE, OF PHILADELPHIA, PENNSYLVANIA, ASSIGNOR TO CROMPTON & KNOWLES LOOM WORKS, OF WORCESTER, MASSACHUSETTS, A CORPORATION OF MASSACHUSETTS

CLUTCH FOR AXMINSTER-LOOM TUBE FRAMES

Application filed November 11, 1929. Serial No. 406,277.

This invention relates to improvements in Axminster looms and it is the general object of the invention to provide means for arresting undue rotation of the yarn spools and effective to stop the loom should the tube frames stick and not move toward the cloth forming position at the proper time.

In Axminster looms tube frames each carrying a yarn spool are mounted on and extend between transporting chains which are given step by step movements to present the tube frames one at a time to an operative position from which they can be moved toward the cloth for the formation of a row of tufts. Transferrer arms are provided to move the tube frames from the chains, but it occasionally happens that one or the other of the ends of the tube frame will become entangled with the chain so that it cannot move downwardly. Under these conditions it is desirable to stop the loom. It is an important object of my present invention to provide a device mounted on the transferrer arm which shall engage the spool to apply friction thereto and at the same time be capable of having holding engagement with the spool to co-act with a stop motion operative to stop the loom should a tube frame stick in the chain.

Certain of the spools at present in use have steel heads with outwardly projecting horizontal flanges and it is a further object of my present invention to provide a plunger on the transferrer arm effective to lie over the flange of the spool head so as to be held in raised position thereby should a tube frame stick in the transporting chain. In this aspect of the invention it is not essential that the device forming an important part of my present invention should apply friction to the spool head.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is an end elevation of a portion of the loom having my invention applied thereto,

Fig. 2 is a front elevation of certain parts shown in Fig. 1 on an enlarged scale, the clutch being in an intermediate position which it assumes when moving toward the tube frame,

Fig. 3 is a view similar to Fig. 2 but with the clutch in engaging position with the tube frame,

Fig. 4 is a top plan view taken in the direction of arrow 4, Fig. 3, and

Fig. 5 is a vertical section on line 5—5 of Fig. 2.

Referring particularly to Fig. 1 I have shown a loom frame 10 and a rotating cam plate 11 having thereon a tappet 12. The latter engages a horizontal arm 13 of a lever 14 pivoted as at 15 to a fixed bracket 16. The upper end of the lever 14 has pivoted thereto as at 17 a link 18 which is caused to reciprocate periodically so that a hooked portion 19 thereof will move to the left as viewed in Fig. 1. A knock-off lever 20 pivoted at 21 has a boss 22 which is adapted to be engaged by the hook 19 under certain conditions.

The right hand end of the link 18 is pivoted as at 23 to the lower end of a vertical push rod 24 the upper end of which is guided through an eye 25. The upper end of the rod is positioned for engagement with some portion of a transferrer device having an arm 26. The latter is pivoted as at 27 and moves downwardly for each advance movement of the transporting chain 28. The power to raise the transferrer arm up and down may be transmitted through a rod 29 and the transferrer arm may be pivoted about a vertical axis 30 on a supporting lever 31.

Under normal operation it is to be understood that the tube frames which are arranged in a series are presented to operative position by the chains 28, only one of which is set forth herein. The transferrer arm 26 will then move around the axis 30, moving the clutches 32, of which only one is set forth herein, toward the tube frame in operative position. Thereafter, by means of rod 29, the tube frame and transferrer arms are lowered

to tuft forming position, and thereafter raised.

Referring more particularly to Fig. 2, each tube frame T comprises a tubular bar 40 to which is attached a spool bearing bracket 41. The latter receives the gudgeon 42 of a yarn spool 43 which may have a pressed steel head 44 provided with a horizontal flange or rim 45. The latter defines one end of the yarn space and may if desired engage a friction spring 46 mounted on top of the bar 40.

The bracket may be provided with a chain engaging member 47 and there may be a hook 48 which has supporting relation with respect to either the bracket as shown herein or the tube frame in any desired manner. The hook normally engages a portion of the transporting chain and supports the weight of the tube frame. The clutch 32 has a vertical wall 49 which engages the hook to move the same toward the spool when the tube frame is to be moved from the chain.

The matter thus far described forms no part of my present invention and may operate substantially in the usual manner. There are two clutches, one for each end of the tube frame and my invention relates more particularly to devices carried by the clutch to engage the yarn spool.

30 During the tuft forming operation the spool is rotated to pay off yarn for the formation of the piles and unless precautions are taken to prevent excess rotation of the spool an amount of yarn will be delivered which 35 will be wasted. In carrying my invention into effect I provide a plunger 50 having a reduced end 51 which extends through a portion of the clutch 32. The plunger is provided with a shoulder 52 to engage a portion 40 of the clutch and limit movement of the plunger toward the tube frame. A pin or similar device 53 passes through the plunger and also extends through certain coils of a tension spring 54, the left hand end of which 45 as shown in Fig. 2 is retained by a screw 55 carried by the clutch.

As shown in Fig. 4 the reduced end 51 lies to one side of the spool bearing member 41 and chain engaging part 47 of the bracket 50 and is adapted to move against the vertical surface 56 of the spool head 44.

In operation, as the clutch moves from the position shown in Fig. 2 to that shown in Fig. 3 the plunger will engage the spool head 44 before the clutch has finished its movement, thereby placing the spring 54 under tension to apply additional friction to the spool head. During the subsequent operation of the loom the transerrer arm 26 will normally move downwardly to carry the tube frame to cloth forming position, but if for any reason the tube frame should be held in raised position the plunger will engage the lower part of the rim 45 of the spool so that further descent 65 will be prevented. Under these conditions

the plunger will engage the spool flange to arrest downward movement of the clutch and transerrer arm before the latter is in position to engage the top of the depressor rod 24. The hook 19 will therefore be in low 70 position and the loom will be stopped.

It is to be understood that if the operation is normal the transerrer device will depress the rod 24 to raise the hook 19 before the rod 18 moves to the left as viewed in Fig. 1, thereby permitting continued loom operation. 75

From the foregoing it will be seen that I have provided a combined friction device and stop motion operating feature which may be carried by the clutch or other part moving 80 with the transerrer arm or device effective to stop the loom by engagement with a part of the spool should the latter be held against normal downward movement.

Having thus described my invention it will 85 be seen that changes and modifications may be made therein by those skilled in the art without departing from the spirit and scope of the invention and I do not wish to be limited to the details herein disclosed, but what I 90 claim is:

1. In an Axminster loom having a group of tube frames which are movable progressively to operative position, means to move the tube frames one at a time from the chain toward cloth forming position, a rotatable spool on each tube frame, a stop motion to stop the loom when a tube frame is improperly held in the chain, and a device acting simultaneously to offer resistance to rotation of the spool and also to co-act with the stop motion to prevent disabling thereof. 95

2. In an Axminster loom having a group of tube frames which are movable progressively to operative position, means to move the tube frames one at a time from the chain toward cloth forming position, a rotatable spool on each tube frame, a stop motion to stop the loom when a tube frame is improperly held in the chain, and a device acting simultaneously to offer resistance to rotation of the spool and also to co-act with the stop motion, to prevent disabling thereof said spool having a head with a surface having a horizontal component to co-act with the device. 110

3. In an Axminster loom having a group of tube frames which are movable progressively to operative position, means to move the tube frames one at a time from the chain toward cloth forming position, a rotatable spool on each tube frame, a stop motion to stop the loom when a tube frame is improperly held in the chain, and a device acting simultaneously to offer resistance to rotation of the spool and also to co-act with the stop motion, to prevent disabling thereof said spool having a head provided with a flange extending in a horizontal direction to cooperate with the device. 120

4. In an Axminster loom having a trans- 125

porting chain, a stopping member to be moved when continued loom operation is desirable and remain at rest when loom operation is to be arrested, a spool carrying frame, a yarn spool thereon, a transfer device to move the spool carrying arm from the chain to cloth forming position, said device to have engagement with the aforesaid member, and means moving with the device to engage the spool 5 and have holding engagement therewith to prevent engagement between the device and stopping member if the spool carrying frame 10 is unable to move toward cloth forming position.

15 5. In an Axminster loom having a transporting chain, a stopping member to be moved when continued loom operation is desired and to remain at rest when loom operation is to be stopped, a tube frame on the transporting 20 chain, a transfer device adapted to move the tube frame from the transporting chain to cloth forming position, said device adapted to cooperate with and move the stopping member, a yarn spool carried by the tube frame 25 and moving therewith, and an element carried by the transerrer device to engage the spool so that when a tube frame is improperly held in the chain said element will co-act with the spool to hold the transfer device in raised position out of engaging position with the member 30 to cause stopping of the loom.

6. In an Axminster loom having a stopping member to be moved when continued loom operation is desired and to remain at rest when loom operation is to be stopped, a transporting chain, a series of tube frames thereon, a transfer device adapted to move a tube frame from the transporting chain to cloth forming position and also cooperate 35 with the stopping member, a spool head and spool carried by the tube frame, and an element mounted on the transfer device and positioned to engage the spool head, the spool head limiting downward movement of the 40 element relatively to the tube frame when the tube frame is improperly held in the transporting chain, said element thereby preventing coacting between the transfer device and the member stopping, whereby the latter remains effective to stop the loom.

In testimony whereof I have hereunto affixed my signature.

JOHN LYLE.
